CLAIM

The ornamental design for a smoking device, as shown.

DESCRIPTION

FIG. 1 is a top plan view of a smoking device, showing my new design;

FIG. 2 is a side elevational view, the opposite side being a mirror image thereof;

FIG. 3 is a front elevational view thereof; and,

FIG. 4 is a rear elevational view thereof.

FIG. 5 is an enlarged, fragmentary front perspective view of the device.
